UNITED STATES PATENT OFFICE

155,830

DESIGN FOR A DOLL

Phoebe L. Mooney, Johnson County, Kans.

Application December 22, 1948, Serial No. 150,324

Term of patent 3½ years

(Cl. D34—4)

To all whom it may concern:

Be it known that I, Phoebe L. Mooney, a citizen of the United States, residing in the county of Johnson and State of Kansas, have invented a new, original, and ornamental Design for a Doll, of which the following is a specification, reference being had to the accompanying drawing, forming part thereof.

Fig. 1 is a front perspective view of a doll showing my new design.

Fig. 2 is a side view of the doll.

Fig. 3 is a back view of the doll.

I claim:

The ornamental design for a doll, as shown.

PHOEBE L. MOONEY.
